UNITED STATES PATENT OFFICE.

IRVING F. WEBB, OF ELIZABETH, NEW JERSEY, ASSIGNOR TO THE SINGER MANUFACTURING COMPANY, OF ELIZABETH, NEW JERSEY, A CORPORATION OF NEW JERSEY.

LIGHTING DEVICE FOR SEWING MACHINES.

Application filed January 23, 1922. Serial No. 531,028.

To all whom it may concern:

Be it known that I, IRVING F. WEBB, a citizen of the United States, residing at Elizabeth, in the county of Union and State 5 of New Jersey, have invented certain new and useful Improvements in Lighting Devices for Sewing Machines, of which the following is a specification, reference being had therein to the accompanying drawings.

10 This invention relates to electric lighting devices for sewing machines and has for an object to provide a lighting attachment of the type disclosed in my copending application Serial No. 522,232, filed December 14, 15 1921, with improved cushioning means for supporting the lighting element or lamp so that it will not be subjected to the pounding vibration of the sewing machine frame, thus permitting the use of lamp-bulbs having 20 filaments of the more delicate types, such as tungsten filaments.

A further object of the invention is to provide a lighting attachment having only a limited range of yielding movement and 25 confined against excessive accidental displacement from its working position.

Still further, the invention has for an object to provide a lighting device which is not susceptible of slow periodic vibrations 30 of large amplitude.

To the ends in view the supporting element of the attachment has secured thereto an overhanging lamp supporting arm from which depend one or more yielding suspension elements or springs. Preferably, two 35 suspension connections are used, one adjacent each end of the lighting element. The lighting element may be in the form of rigidly associated electric lamp-socket, bulb and reflector elements, sustained by said suspension 40 means horizontally below the overhanging lamp-supporting arm. When two suspension connections are employed, one is preferably attached to the reflector and the 45 other to the lamp-socket; said reflector being preferably made of rather heavy sheet-metal to increase the inertia of the floating parts. The suspension means, when in 50 spring form, is made sensitive enough to be materially distended by the weight of the lighting element. The lamp-supporting arm is preferably clamped upon an apertured cylindrical head in line with the axis 55 of the center line of the lamp-socket and bulb, for such circular adjustment about

such axis as may be necessary to position the lamp-supporting arm above the lamp. The conductor-cord preferably passes freely through the hollow cylindrical supporting head to the lamp-socket and serves to prevent excessive lateral displacement of the lamp-socket from its pendant position and to damp any swinging or slow periodic vibrating tendency of the lighting element as a whole.

In the accompanying drawings, Fig. 1 is a rear side elevation of a sewing machine to which is applied a lighting attachment embodying the present improvement. Fig. 1^a is a detail sectional view. Fig. 2 is a top plan view of the lighting attachment as applied to the machine; the standard or vertical member of the sewing machine goose-neck being shown in horizontal section and Fig. 3 is a section on the line 3, 3, Fig. 1.

The particular embodiment of the invention hereinafter described is illustrated as applied to a sewing machine having a bed 1, standard 2 and overhanging arm 3 terminating in the head 4 which carries the 80 usual presser-foot 5 and reciprocating needle 6. The lighting element preferably comprises the lamp-socket 7, reflector 8 and lamp-bulb 9. The reflector 8 is preferably made of rather heavy sheet-metal and constitutes the upper half of the lamp-guard 10 which is securely clamped in a well-known manner at 11 upon the socket 7.

Disposed above the lighting element is the lamp-supporting arm 12 which is preferably made as long as the lighting element and is curved downwardly at its free end to follow the curve of the reflector 8 and approach the tip end 13 of the latter which is suspended from the arm 12 by the 90 spring 14. A suspension connection is also preferably made adjacent the socket end of the lighting element as by providing an ear 7' and spring 15. The ear 7' is preferably circularly adjustable about the axis of the 95 socket 7 and is securely clamped in adjusted position relative to said socket by means of the tubular thumb-nut 7" having a reduced threaded extremity 7''' which enters the aperture 7^a in the ear 7' and is screwed 100 into the socket, as shown in Fig. 1^a. The springs 14 and 15 suspend and steady the lamp-socket and bulb substantially horizontally at two spaced points i. e., at the opposite ends of the lighting element, and are 110

sensitive enough to be materially distended by the weight of the suspended parts. The end of the arm 12 adjacent the lamp-socket 7 is preferably extended vertically for a short distance and is bent into circular form and fitted with a thumb-screw 16 to provide a clamp 17, the center of which is substantially coincident with the center line of the lighting element. The clamp 17, when employed, may embrace a hollow horizontal cylindrical head 18 of a vertical post 19 to the lower end of which is fixedly secured a serrated clamping disk 20. Rigidly secured to and extending below the post 19 is the threaded screw-pin 21 which passes through the serrated clamping disk 22 spot-welded or otherwise suitably fixed to the horizontal arm 23 of an angle-piece 23-26 and is secured in position by the thumb-nut 24. The horizontal arm 23 of the angle-piece may have spot-welded to its underside a serrated clamping disk 25 permitting the post 19 to be reversed from above to below such element; either of the disks 22 and 25 being adapted to mesh with the disk 20 to lock the post 19 in adjusted position relative to the angle-piece 23-26.

The vertical arm 26 of the angle-piece may be adjustably swivelled horizontally to the U-shaped support or base element 27 by means of the screw 26^a, thumb-nut 26^b and coacting serrated clamping disks 26^c secured, respectively, to the arm 26 and support 27, as disclosed in my said copending application; the U-shaped support having feet 28 to which pads 29 of friction material are secured. A flexible strap 30 of leather, canvas or the like, having a buckle 30' passes through the slots 31 in the legs of the support 27 and adapts the device to be readily secured in any desired position to any desired part of the sewing machine gooseneck.

The conductor-cord 32 is preferably passed to the socket 7 through the aperture 33 in the head 18 and serves in cooperation with said head to damp any swinging motion accidentally imparted to the suspended elements. This construction also prevents excessive lateral displacement of the socket 7 from its pendant position.

The spring 15 may be omitted and the head 18 and cord 32 depended upon as a yielding auxiliary support or steadyng means for the lighting element suspended horizontally by a single suspension element 14. The spring 15, when used, may also be considered as a steadyng element cooperating with the head 18 and cord 32 to maintain the lighting element yieldingly in its horizontal working position.

Only one embodiment of the invention has been shown and described although it is obvious that the invention is susceptible of

various other specifically different embodiments within the spirit and scope of the invention as defined in the appended claims. 65

Having thus set forth the nature of the invention, what I claim herein is—

1. A lighting device comprising supporting means adapted to be secured to the frame of a sewing machine, an electric lamp-socket and semi-cylindrical reflector rigidly connected in end-to-end relation, and suspension springs between said supporting means and said socket and reflector, respectively, 75 said springs supporting said socket and reflector horizontally.

2. A lighting device comprising a support adapted to be secured to the frame of a sewing machine, a substantially horizontally disposed lighting element including a lamp-socket, bulb and horizontal reflector rigidly connected to said lamp-socket, a lamp-supporting arm connected at one end to said support and extending above and longitudinally of said lighting element, and suspension springs connecting the lamp-socket and the free end of said reflector, respectively, 85 with said supporting arm.

3. A lighting device comprising a support adapted to be secured to the frame of a sewing machine, a substantially horizontally disposed lighting element including a lamp-socket, bulb and reflector, a lamp-supporting arm connected at one end to said support and extending above and longitudinally of said lighting element, and yielding means for suspending said lighting element substantially horizontally from said support, said arm being circularly adjustable 100 relative to said support about the center line of the lighting element as an axis.

4. A lighting device comprising a supporting base adapted to be secured to the frame of a sewing machine, a head universally adjustable on said base, an arm circularly adjustable on said head about a substantially horizontal axis, and a lighting element suspended substantially horizontally from said arm and having its axis in substantial coincidence with the axis of adjustment of said arm. 110

5. A lighting device comprising a lighting element including a lamp-socket and bulb, a tubular supporting head spaced from said socket and having its aperture substantially in line with the center line of said socket, a supporting arm secured to said head and overhanging said lighting element, suspension springs supporting said lighting element from said arm, and a conductor-cord passing through said head to said lamp-socket. 115 120

In testimony whereof, I have signed my name to this specification.

IRVING F. WEBB.
